Patented Dec. 16, 1902.

W. L. WALTON.

CLEANING ATTACHMENT FOR DISK IMPLEMENTS.

(Application filed May 29, 1902.)

(No Model.)

UNITED STATES PATENT OFFICE.

WILLIAM L. WALTON, OF NECHE, NORTH DAKOTA.

CLEANING ATTACHMENT FOR DISK IMPLEMENTS.

SPECIFICATION forming part of Letters Patent No. 715,910, dated December 16, 1902.

Application filed May 29, 1902. Serial No. 109,534. (No model.)

To all whom it may concern:

Be it known that I, WILLIAM L. WALTON, a citizen of the United States, residing at Necho, in the county of Pembina and State of 5 North Dakota, have invented a new and useful Cleaning Attachment for Disk Implements, of which the following is a specification.

This invention relates to that class of seed-drills in which pairs of disks mounted revolvably at angles to each other are employed for the purpose of opening the furrows to receive the seed.

My invention has for its object to provide 15 a means for cleaning the said disks which shall be simple, easily applied, and efficient in operation.

With these ends in view my invention specifically consists in the improved construction and arrangement of such cleaning device or attachment which will be hereinafter fully described, and particularly pointed out in the claims.

In the accompanying drawings, Figure 1 is 25 a side view showing a drill-tube and the portion of a frame of a grain-drill carrying the revolving disks and showing my improved cleaning device attached in position for operation. Fig. 2 is a top plan view of the 30 same. Fig. 3 is a perspective view showing the cleaner detached. Fig. 4 is a perspective view showing a modified construction of the cleaner. Fig. 5 is a plan view showing my invention arranged in connection with a 35 pivotal washer which it may be found desirable sometimes to use. Fig. 6 is a perspective view showing the pivotal washer detached. Fig. 7 is an end or edge view of the cleaner shown in perspective in Fig. 3.

40 Corresponding parts in the several figures are indicated by like characters of reference.

My improved cleaning attachment in its simplest form is composed of a piece of steel wire 1, at one end of which is formed an eye 2 and the outer end of which is flattened to 45 form a blade 3, which is hardened or tempered and ground to a cutting edge 4, which latter is disposed oppositely to the eye 2. The wire 1 is bent at the intersection of the blade 3 with the unflattened portion, which forms a shank 5, which latter is possessed of some 50 degree of resiliency.

6 designates a portion of the frame of the seed-drill, and 7 is the drill-tube, to which and in rear of which are formed lugs 8, through 55 which passes a transverse bolt 9, upon the ends of which my improved cleaning devices are mounted, as shown in Fig. 2, the shanks 5 being extended downwardly and rearwardly over the rear edge of the segmental shield 60 10, which constitutes a portion of the frame, and the blades 3 being disposed upon the outer sides of the rotary cutter-disks 11. The arrangement of the blades 3 with relation to the cutter-disks will be readily understood 65 by reference to Figs. 1 and 2 of the drawings, from which it will be seen that the blades, with their cutting edge facing in a rearward direction, are extended downwardly and forwardly from the shanks 5, the points of said 70 blades terminating at a point which in practice should be only about two inches from the periphery of the cutting-disk 11. When the latter rotates, it will thus be seen that the dirt adhering thereto will be removed by 75 a long sweeping motion, which renders such removal much easier and much more effective than if the cutting-blades were arranged radially, or approximately so, with relation to the disks. 80

It will be seen that in order to provide for the attachment of the cleaning devices in such a manner that the blades 3 shall not only have the requisite slope with relation to the disks 11, (which is brought about by bending the wire or piece of material of which the device is formed to form the angle 14, as shown clearly in Figs. 1, 4, and 5 of the drawings,) but also to cause it to lie with its edge flat against the face of the disk, it becomes 85 necessary to bend the shank portion 5 angularly to the plane occupied by the edge of the blade 3, as will be understood by reference to Fig. 7 of the drawings, by reference to which it will appear that the shank portion 90 5, which has already been bent at an angle to the blade 3, is further bent out of the plane of said plate. Moreover, the eye 2, which is formed at the end of the shank 5, is 95 twisted in such a manner that its bearing or contact points 15 15 on opposite sides of the axis thereof shall be included in a line drawn through the axis of said eye and through the center of the cutting edge 4 of the cleaning 100

device. This construction is extremely important, because without it if the nuts were tightened upon the bolt upon which the cleaning devices are mounted an unequal pressure upon the blades of the same would be the result, one end of the blade being thus left in less rigid contact with the adjacent disk 11 than the other end of said blade, fine roots and other obstructions would gradually become wedged under the looser end, and the successful operation of the device thus be interfered with.

In Fig. 4 of the drawings I have shown a modified construction of my improved cleaner, 15 which consists in attaching to the flattened portion 3 a separate tempered blade 17, having the cutting edge. This construction may sometimes be found preferable. In other respects the construction of the cleaner is identical with that already described.

I have found that sometimes the play of the disks 11 in their bearings will cause a somewhat uneven pressure upon the blade and cutting edge of my improved cleaner or 25 between said blade and cutting edge and the face of the disk. To obviate the difficulty caused thereby, I have devised the pivotal washer illustrated in Figs. 5 and 6 of the drawings, and which consists of a metallic 30 washer the two sides of which are connected by bent portions or bridge-pieces 20, the said opposite sides being designated 21. Each side of the washer is provided with a transverse rib 22, projecting outwardly and forming 35 the bearings upon which the washer may have a pivotal or swinging movement with relation to the adjacent clamping or tightening parts. When a washer of this construction is adjusted upon the connecting-bolt 9, 40 with its sides 21 engaging opposite sides of the eye 2 of the cleaning device, the latter will be permitted a limited pivotal movement, whereby it is enabled to adjust itself to slight changes in the position of the disks 11, 45 resulting from reasons that have been above referred to.

From the foregoing description, taken in connection with the drawings hereto annexed, the operation and advantages of my invention 50 will be readily understood.

It will be observed that the points of my improved cleaners are extended well in a downward direction. The removal of the dirt adhering to the disk thus begins soon after the 55 disk leaves the ground in its progressive rotation and much of the danger of clogging is avoided. The dirt adhering to the disk is loosened as soon as it comes in contact with the point of the cutter and will be gradually 60 and easily detached, the weight of the dirt causing it to drop behind the disk in a position where the operative parts of the device will not be interfered with. The provision which I have made for maintaining an even 65 pressure of the edge of the cleaner upon the face of the disk makes it practically impossible for particles of roots and other obstruc-

tions to become wedged in the device and interfering with its operation. All obstructions will eventually slide off at the rear edge of the 70 disk. Whenever it shall be desired not to use the cleaners, the blades may be simply lifted off from contact with the disks, where they are normally held with a considerable degree of tension. When thus released, the 75 said cleaners may be permitted to swing freely behind and between the disks, remaining supported loosely upon the bolts which engage the eyes of said cleaners. It is evident that when the cleaners are thus disposed there 80 will be a considerable reduction in the power required to propel the machine, inasmuch as the frictional contact of said cleaners with the disks is avoided. It is obvious that the cleaners may be restored to operative position as 85 easily and as swiftly as they may be released. By my improved cleaners the adhering dirt is removed before it reaches the top of the frame. Hence there is no danger of its clogging or filling in between the top of the frame 90 and the disks, and the power required to lift the adhering dirt to this point is saved.

Other advantages might be mentioned; but they will be readily apparent to any one skilled in the art to which my invention appertains 95 and need not be further enumerated.

I desire to state that while I have described the preferred form or forms of my invention I do not consider myself as limited as regards details, but reserve the privilege of making 100 any such further changes, alterations, or modifications as may suggest themselves in practice and which may be resorted to without departing from the spirit of my invention.

Having thus described my invention, I 105 claim and desire to secure by Letters Patent of the United States—

1. A disk-cleaner consisting of a blade, a shank bent at an angle to said blade and an eye formed upon said shank and bent out of 110 the plane of the latter, substantially as set forth.

2. A disk-cleaner consisting of a blade, a shank bent at an angle thereto and further bent so as to lie in a different plane from the 115 blade and its cutting edge, and an eye formed upon said shank and bent out of the plane of the latter, substantially as set forth.

3. A disk-cleaner composed of a blade, a shank bent at an angle to said blade and further bent so as to lie in a plane different from the cutting edge of the blade, and an eye formed upon said shank and bent until the contacting points on opposite sides of its axis shall be included in a line drawn through said 125 axis and through the center of the cutting edge of the blade, substantially as set forth.

4. The combination of a frame supporting roller-disks, lugs upon said frame, a bolt extending through said lugs and the disk-cleaners mounted upon said bolt, said cleaners having twisted eyes engaging the bolt and nuts bearing against said twisted eyes to force the blades of said cleaners with an even pres-

sure against the disks, substantially as set forth.

5. The combination of a frame supporting roller-disks and having lugs formed thereon, 5 a bolt extending through said lugs, the cleaners comprising blades bearing against the disks, and shanks having eyes engaging the bolt whereby the said cleaners when not required for use may be disengaged by simply 10 swinging them out of contact with the disks, substantially as set forth.

6. The combination of a frame supporting roller-disks and having lugs, a bolt extending through said lugs and the cleaners comprising 15 blades, shanks bent at an angle to said blades and further bent out of the plane of the blades and their cutting edges, and twisted eyes formed upon the ends of said shanks, the points of contact of said eyes with 20 the fastening means on opposite sides of the axis of said eyes being included in a line drawn through said axis and through the center of the cutting edges of the blades, substantially as set forth.

25 7. The combination with a disk-cleaner comprising a shank carrying a blade and having an eye at its opposite end, of a pivot-washer having its sides or halves connected by bridge-pieces whereby said sides are caused

to lie on opposite sides of the eye of the 30 cleaner, said sides being provided with outwardly-extending ribs or bearings, substantially as set forth.

8. The herein-described washer composed of bridge - pieces uniting the semicircular 35 halves of the washer, said halves being provided with centrally-disposed outwardly-extending ribs, substantially as set forth.

9. A disk-cleaner comprising a shank having at one end a blade and at the other end 40 a twisted eye, with the contacting points of the eye disposed in a line drawn through the axis of said eye and through the center of the cutting edge of the blade, in combination with a pivot-washer having bridge-pieces whereby 45 the opposite sides of the washer are adapted to engage opposite sides of the eye of the cleaner, said washer being provided with oppositely-disposed outwardly-extending ribs, a connecting-bolt and clamping means, sub- 50 substantially as set forth.

In testimony that I claim the foregoing as my own I have hereto affixed my signature in the presence of two witnesses.

WILLIAM L. WALTON.

Witnesses:

DONATIEN MALO,

WILLIAM ALEXANDER MURPHY.
